UNITED STATES PATENT OFFICE

PETER MATTNER, OF ST. LOUIS, MISSOURI, ASSIGNOR TO JOHNSON-STEVENS & SHINKLE SHOE COMPANY, OF ST. LOUIS, MISSOURI, A CORPORATION OF MISSOURI

METHOD AND APPARATUS FOR WEAVING

Application filed March 23, 1929. Serial No. 349,337.

This invention pertains to a method and apparatus for weaving a web or fabric of strips, such as strips of leather.

In the manufacture of shoes, and more particularly ladies' shoes, a shoe constructed of a woven fabric of leather strips has become very popular. It is one of the purposes of this invention to provide a method and machine by means of which a suitable woven leather fabric may be made in a simple manner and without prohibitive expense.

A further object of this invention is to provide such method and apparatus whereby a continuous warp of leather strips or strands may be supplied to a suitable loom out of which the woven leather fabric may be formed.

Another object is to provide a method in which the splicing of individual strips constituting the warp may be obviated.

Another object is to provide a method and apparatus by which a continuous broad band of material is cut into strips and the cut strips supplied as warp to the weaving loom.

Another object is to provide such a device in which the material may be cut against a suitable backing so as to insure smooth edges to the strips.

Another object is to provide improved weaving mechanism by means of which the flat strips may be handled in a simple and convenient manner during the weaving operation.

Further objects will appear from the following description, taken in connection with the accompanying drawings, in which—

Figure 1 is a side view of a machine embodying this invention;

Figure 2 is a plan view of the same;

Figure 3 is a rear view of a portion of the same, taken about on line 3—3 of Figure 1;

Figure 4 is a detail front view of one of the heddles;

Figure 5 is a detail of the mechanism for winding up the web; and

Figure 6 is a detail sectional view through the cutter shaft and roller, illustrating the cutting operation without a backing.

Referring to the drawings, 1 designates a frame having a superstructure 2 on which are mounted, in the usual manner, a pair of heddles 3 operated by treadles 4 in the usual manner. A sill or support 5 on the front of the machine supports the woven fabric which passes thereover to be wound on a suitable roll 6. A batten 7 pivoted at 8 on the frame may be of any suitable construction.

Mounted on the rear of the machine is a reel 9 upon which a broad band 10 of leather or other suitable material is wound. The band 10 may be of any material of which the finished fabric is to be composed. In cases of such material as leather, which comes as hides in relatively short lengths, the band 10 may be made up of a series of such lengths suitably matched and spliced together. A second reel 11 is mounted on the frame 1 and carries a similar band 12 of suitable backing material, such as paper or the like, which is used for backing the band 10 during the cutting operation, as will presently be more fully described. The bands 10 and 12 pass upwardly from their rolls through a guide 13 on the rear of the frame 1 to the cutting roll.

Mounted on the upper part of the rear of the machine is a sub-frame 14 in which is mounted a backing roll 15 adapted to rotate on a shaft 16 having bearings in the frame 14. Mounted above the shaft 16 is a shaft 17 which carries a series of sharp edged cutting discs 18. The discs 18 are spaced apart at intervals such as to provide the desired width for the cut strips. The roll 15 may be constructed of iron or steel, in which case the band 12, of paper or the like, is made to pass over the roll below the band 10, so that the cutting discs 18, after cutting through the band 10, may cut into the paper, thereby providing a clean-cut edge for the leather strips.

Mounted on a stub shaft 19 on the frame 14 is a ratchet wheel 20. A lever 21 pivoted at 22 on the frame 14 carries a pair of pawls 23 adapted to engage the ratchet 20 in such a manner that by swinging the lever 21 up and down on its pivot 22 the pawls 23 will

operate to rotate the ratchet 20 and its shaft 19. The shaft 19 is geared to the shaft 16 so as to rotate the latter for feeding the material. The material is cut into strips as 5 it is fed by the roll 15.

The frame 14 is so positioned on the loom frame 1 that the cut strips 24 may be passed directly to the heddles 3 so as to form the warp from which the woven material is 10 made.

The construction of the heddles 3 is illustrated in Figure 4. A series of flat straps 25 is mounted in the heddle frame in any suitable manner and properly spaced apart. 15 In the construction illustrated, the strips are strung on bars 26 and 27 with suitable spacing sleeves 28 therebetween. The middle portion 29 of each strap 25 is twisted through ninety degrees so as to stand cross-wise of the strips 24. Each portion 29 is provided with a transverse slot or notch adapted to receive one of the strips 24 as illustrated in Figure 4. These notches serve 20 to hold the strips in a position edgewise to the weft when the latter is inserted. The strips 24, where they pass between the straps 25 on the other heddle, to which they are not attached, are turned edgewise, as shown at 24^a in Figure 4. This is in order that 25 they may slide up and down between the portions 29 of the straps 25 during the up and down movement of the heddles 3. The strips 24 are, therefore, free to move up and down past each other as the heddles are 30 raised and lowered. The weft is provided by a single strip wound upon a suitable shuttle which is passed by hand or otherwise through the shed formed in the usual manner by the operation of the heddles. The 35 weft strip is shown at 30 as wound on a shuttle 31.

The finished web 32 is wound upon the reel 6. Said reel is fixed to a shaft 33, which also has fixed thereto at one end a ratchet 45 34, as illustrated in Figure 5. An auxiliary reel 35, mounted on the shaft 33 and connected to the ratchet 34 by means of a spring-pressed pawl 36, is adapted to have wound thereon a cord 37. This cord passes 50 over a pulley 38 and has attached thereto a weight 39. The weight 39 operates to rotate the reel 6 as the finished web is fed along, so as to continuously wind the same. When the cord 37 has been paid out, it may 55 be re-wound by turning the reel 35 by means of a suitable crank 40.

The roll 15 may be constructed of a softer material, such as fiber, in which case the band 10 may be cut without the use of a 60 backing strip as illustrated in Figure 6. In this case the cutting edge of the disc 18 engages the roll 15.

In accordance with the method of the present invention, the band 10 is first made 65 up into a continuous band by suitably splicing

ing together sections of material. The band 10 is usually the full width of the fabric to be woven, although two bands may be fed side by side if a broader web is required. The band is cut into narrow strips by the cutters 18 working against the backing 12, or, as shown in Figure 6, without the backing. After passing the cutters 18, the cut strips are supplied to the weaving mechanism by which they are separated in appropriate manner to form the shed through which the weft strip 30 is passed by means of the shuttle 31. Each weft strip is suitably compacted by means of the batten 7 in the usual manner. The material is fed forward as desired by operating the lever 21.

It will be seen, therefore, that this invention provides a simple method and mechanism for weaving fabrics of strips or strands of leather or the like. Supplying the material in the form of a band 10, which may have its component sections spliced together before-hand, obviates the necessity of splicing the sections of each strip of the warp in order to provide continuous strips. The previously spliced band is cut into narrow strips which are fed directly as warp to the weaving mechanism. This is then woven into a suitable web in the usual manner. The apparatus is simple, easily constructed and may be operated by unskilled labor.

It is obvious that parts of the apparatus may be found to be useful without reference to other parts thereof, and the use of such sub-combinations is contemplated by this invention. It is further obvious that various changes, within the scope of the appended claims, may be made in the details of the method or construction without departing from the spirit of this invention. It is, therefore, to be understood that this invention is not to be limited to the specific details shown and/or described.

Having thus described the invention, what is claimed is:

1. A machine for weaving fabrics, comprising, means for feeding a wide band of weaving material simultaneously with a similar band of backing material, means for cutting the weaving material into a plurality of strips against the backing material, and weaving mechanism mounted to receive the cut strips as the warp for the fabric to be woven.

2. A machine for weaving fabrics, comprising, a feed roll adapted to receive a wide band of weaving material, a reel for the weaving material, a second reel to hold a similar band of backing material, a guide adapted to guide both bands to said feeding roll, a plurality of cutting discs cooperating with said roll to cut the weaving material into a plurality of strips, and weaving mechanism mounted to receive the cut strips as the warp for the fabric to be woven.

3. A machine for weaving fabrics, comprising, means for feeding a wide band of material and cutting the same into a plurality of strips, and weaving mechanism mounted to receive the cut strips as the warp for the fabric to be woven including heddles having means for holding the warp strips edgewise to the weft.

4. A machine for weaving fabrics, comprising, means for feeding a wide band of material and cutting the same into a plurality of strips, and weaving mechanism mounted to receive the cut strips as the warp for the fabric to be woven including heddles having straps provided with notches adapted to hold the warp strips edgewise to the weft.

5. In the art of weaving fabrics, the method comprising, feeding a broad band of material, and cutting the band against a band of backing material into strands to provide the warp for the woven fabric.

6. In the art of weaving fabrics, the method comprising, feeding a broad band of material with backing material therebetween to a cutter, and cutting the band against the backing material into strands to provide the warp for the woven fabric.

7. A machine for weaving fabrics comprising, a feed roll, means for feeding a wide band of weaving material over said roll with a band of backing material therebetween, a plurality of cutting discs cooperating with said roll to cut the weaving material against the backing material into a series of adjacent flat strips, and weaving mechanism adapted to receive the cut strips as the warp for the fabric to be woven.

8. A machine for weaving fabrics comprising, a feed roll, means for feeding a wide band of weaving material over said roll with a band of backing material therebetween, a plurality of cutting discs cooperating with said roll to cut the weaving material against the backing material into a series of adjacent flat strips, said roll being positioned so as to discard the backing material after cutting, and weaving mechanism adapted to receive the cut strips as the warp for the fabric to be woven.

9. A machine for weaving fabrics, comprising, a feed roll adapted to receive a wide band of weaving material, a reel for the weaving material, a second reel to hold a similar band of backing material positioned to pass the backing material underneath the weaving material to said feed roll, and a plurality of cutting discs cooperating with said roll to cut the weaving material against the backing material into a plurality of strips.

10. A machine for weaving fabrics, comprising, a feed roll adapted to receive a wide band of weaving material, a reel for the weaving material, a second reel to hold a similar band of backing material positioned

to pass the backing material underneath the weaving material to said feed roll, a plurality of cutting discs cooperating with said roll to cut the weaving against the backing material into a plurality of strips, and weaving mechanism mounted to receive the cut strips as the warp for the fabric to be woven.

11. A machine for weaving fabrics, comprising, a feed roll adapted to receive a wide band of weaving material, means for feeding a broad band of weaving material to said roll, and a plurality of cutting discs engaging said roll to cut the material into a plurality of strips, said roll being of relatively soft material adapted to receive the cutting edges of said discs.

12. A machine for weaving fabrics, comprising, a reel for the weaving material, a plurality of cutting discs adapted to cut the weaving material into a plurality of strips, and a relatively soft backing roll engaging said discs.

13. A machine for weaving fabrics, comprising, a reel for the weaving material, a plurality of cutting discs adapted to cut the weaving material into a plurality of strips, a relatively soft backing roll engaging said discs, and weaving mechanism mounted to receive the cut strips as the warp for the fabric to be woven.

In testimony whereof I affix my signature this 31st day of October, 1928.

PETER MATTNER.
